UNITED STATES PATENT OFFICE.

LOUIS JOSEPH SIRACUSANO, OF ASTORIA, NEW YORK, ASSIGNOR TO NATIONAL FABRIC AND FINISHING COMPANY, OF NEW YORK, N. Y., A CORPORATION OF MASSACHUSETTS.

DESIGN FOR A PRINTED TEXTILE FABRIC OR THE LIKE.

Application filed August 30, 1928. Serial No. 27,993. Term of patent 3½ years.

To all whom it may concern:

Be it known that I, LOUIS JOSEPH SIRACUSANO, a citizen of the United States, residing at Astoria, in the county of Queens and State of New York, have invented a new, original, and ornamental Design for Printed Textile Fabrics or the like, of which the following is a specification, reference being had to the accompanying drawing, forming part thereof.

The single figure of the drawing is a plan view of a piece of printed textile fabric showing my new design. The irregular shaped

areas of fabric or the like embodying my design are printed in contrasting colors and varying shades of the same color, and this is indicated in the accompanying drawing by the varied cross hatching of said irregular shaped areas; like cross hatching representing like colors or shades of color throughout the piece of fabric shown.

I claim:

The ornamental design for a printed textile fabric or the like, as shown.

LOUIS JOSEPH SIRACUSANO.
